JEWELRY FINDING FOR AN EARRING ORNAMENT

Abraham Sutain, Brooklyn, N. Y.

Application February 7, 1955, Serial No. 34,384

Term of patent 14 years

(Cl. D45—9)

Fig. 2.

Fig. 1.

Fig. 3.

Fig. 1 is a front elevational view of a jewelry finding for an earring ornament, showing my new design.

Fig. 2 is a top plan view thereof.

Fig. 3 is a side view thereof.

I claim:

The ornamental design for a jewelry finding for an earring ornament, substantially as shown.
